UNITED STATES PATENT OFFICE.

JOHN POKORNEY, OF BURWELL, NEBRASKA.

LEVER-CONTROL BOLT FOR DOORS.

Application filed January 8, 1927. Serial No. 159,860.

The invention relates to lever controlled bolts for doors and has for its object to provide a device of this character comprising a single pivoted lever having connections with the door bolts, for instance the upper and lower bolts and by pressure on the lever the bolts are simultaneously moved to open position. The device is particularly adapted for exit doors of amusement houses or buildings where large crowds of persons collect.

A further object is to provide a casing on the door substantially U-shaped in horizontal cross section and having rollers over which flexible members connected to the bolts extend, and to position the pivoted lever whereby its end will be disposed in a recess in the casing between adjacent rollers and in a slidable bolt slidably mounted on the rollers and within the casing positioned whereby it may be moved over the end of the lever within the casing recess for locking said lever against movement.

With the above and other objects in view the invention resides in the combination and arrangement of parts as hereinafter set forth, shown in the drawing, described and claimed, it being understood that changes in the precise embodiment of the invention may be made within the scope of what is claimed without departing from the spirit of the invention.

In the drawing:

Figure 1 is a perspective view of a portion of conventional form of door, showing the device applied thereto.

Figure 2 is a vertical transverse sectional view through the looking device and a door.

Figure 3 is a horizontal sectional view taken on line 3—3 of Figure 1.

Referring to the drawing the numeral 1 designates a portion of a conventional form of swinging door and 2 casings secured to said door adjacent its upper and lower ends, and in which are slidably mounted bolts 3 which are normally forced upwardly and downwardly by means of the coiled springs 4, whereby said bolts are forced into the keepers 5 and 6, carried adjacent the upper and lower ends of the door. Secured to the face of the door by means of screws 7, which extend through the lugs 8, is a casing 9, which casing is U-shaped in horizontal cross section and has rotatably mounted therein spaced rollers 10 and 11, and over which rollers the flexible members 12 which are connected to the sliding bolts 3 extend and

are guided in their movement during an unbolting or bolting operation. Casing 9 is provided with a recess 13 into which the transverse portion 14 of the pivoted lever 15 extends and to the ends of the transverse portion 14 the adjacent ends of the flexible members 12 are anchored at 15. It will be seen that when a person imparts a push on the handle member 17 of the lever 15, said handle member will cause the lever to rock on its pivotal point 18, thereby moving the transverse portion 14 of the lever outwardly from the recess 13, consequently impart a simultaneous pull on the chains 12 and move the sliding bolts 3 to open position, and the continued push will swing the door to open position, which is particularly desirable for exit doors in houses of public gathering, where in cases of emergency it is necessary to quickly open the doors.

It is obvious that at times it is desirable to lock the bolts or lever against operation, and to accomplish this result a sliding bolt 19 is slidably mounted within the U-shaped casing 9 within the arcuate portions 20 of the casing and which bolt also slidably engages the rollers 10, thereby utilizing said rollers for guiding means, consequently allowing the device to be cheaply manufactured. The bolt 19 is provided with an outwardly extending finger engaging lug 21 for holding the bolt in its closed or open position. The lug 21, when the bolt 19 is in open position is moved into the recess 22 as clearly shown in Figure 1, and when the bolt is in closed or locked position the lug 21 is moved into the recess 23 after a longitudinal movement of the bolt to a position where its lower end will overlie the portion 14 of the lever, and the lug is moved into the recess 23 by a partial rotation of the bolt 19. It will be noted that the casing 9 as a whole can be stamped from a single piece of material, consequently the cost of the casing is reduced to a minimum.

From the above it will be seen a controlling means is provided for multiple bolts whereby the bolts may be simultaneously operated by a single operating lever and by a single movement of the lever, and sliding bolt means is provided, guidable on the rollers within the casing for cooperating with the pivoted lever for locking the same against movement when desired.

The invention having been set forth what is claimed as new and useful is:

1. The combination with a door having oppositely disposed spring latched bolts, of means for simultaneously moving said bolts to open positions, said means comprising a casing carried by the door between the spring actuated bolts, a plurality of rollers within the casing, flexible members connected to the bolts and extending under said rollers, a pivoted lever pivoted at a right angle to the casing and extending into a recess in the casing between adjacent rollers, the ends of said flexible members being connected to the lever in the recess of the casing, a slidable bolt guided within the casing, means for moving said bolt longitudinally to an overlapped position over the lever in the recess of the casing, said bolt being slidably mounted on the rollers.
2. The combination with spring actuated latching bolts carried by a door, of operating means for said bolts, said operating means comprising a casing carried by the door between the bolts, a plurality of rollers within the casing, flexible members connected to the bolts and extending towards
- each other under the rollers within the casing, a pivoted lever, one end of said lever being disposed in a recess in the casing and connected to the flexible members, and a slidable lever holding bolt within the casing and positioned whereby it may be moved to a position over the lever end within the casing, said bolt having a bearing on adjacent rollers.
3. The combination with spring actuated bolts carried by a door, of an operating mechanism for said bolts, said operating mechanism comprising a casing, a pivoted lever, spaced rollers within said casing, one end of the lever extending into a recess of the casing, flexible members connected to the bolts and to the lever end and extending under the rollers, and a latching bolt carried by the casing and cooperating with the lever for locking the same against pivotal movement.

In testimony whereof I hereunto affix my signature.

JOHN POKORNEY.
